WATERPROOF FOLDABLE HANDBAG FOR BABY ACCESSORIES

Inez Holland, Rockville Centre, N. Y.

Application September 27, 1946, Serial No. 699,837

2 Claims. (Cl. 150—34)

1

This invention relates to a handbag, and particularly to a bag in which to carry infants' garments and accessories, such as bottles, diapers, and the like.

It is a particular object of the invention to provide a handbag of relatively large carrying capacity, but which may be folded into very compact form when not in use.

It is another object of the invention to provide a bag of the type described which has means for receiving and securing a pair of bottles in such fashion that there will be no danger of breakage by striking one against the other.

It is another object of the invention to provide a foldable bag for infants' garments and bottles, in which bottle-receiving loops are secured to the opposite margins of one side of the bag and are so disposed that the empty bag may be flattened and folded in half along a line defined by the upper edges of said bottle loops.

It is another object of the invention to provide a bag as described having a waterproof pocket in which wet or soiled diapers may be carried without the possibility of contaminating the fresh diapers or other accessories which remain within the bag.

It is another object of the invention to provide a bag as described in which the wet diaper compartment comprises a waterproof envelope secured internally of the bag only at its upper edge, and which is of such size that the bag per se may be disposed within the said envelope when the bag is not in use, to protect the exterior of the bag against soiling.

It is another object of the invention to provide a bag of waterproof and soil resistant material, said material being quilted to have insulation characteristics which will protect the contents of the baby bottles against temperature change.

Infants' wear and accessories are traditionally of pale pink or blue, either of which colors is easily soiled by casual handling while the goods are on display in a store, or while the goods are being packed for delivery. Purchasers are prone to return merchandise—and particularly merchandise of the nature of infants' accessories—which they receive in any but a completely "fresh" form. As a result, stores frequently are compelled to sell shopworn or soiled merchandise at very substantial reductions in price.

It is an important feature of the present invention that the internal envelope adapted to receive soiled diapers is of such size and arrangement that the bag per se may be folded or inserted into the envelope to protect the exterior of the

bag against soiling or damage while the bag is on the shelves of the store, and while the bag is being shipped to the purchaser. Also, the diaper envelope may be used as a means of protection of the bag when it is not in use in the home.

By making the envelope of a substantially colorless transparent material such as the colorless vinyl plastic films, the attractive exterior color of the merchandise is not concealed when the bag is contained therein, and the merchandise may be attractively displayed.

Other features and advantages of the present invention will be apparent from a study of the accompanying drawings and the description relative thereto.

In the accompanying drawings:

Fig. 1 is a perspective of a bag pursuant to the present invention, having been folded and inserted into the diaper envelope thereof;

Fig. 2 is a perspective showing the bag in the stage of removal from or insertion into the diaper envelope;

Fig. 3 is a top perspective view of the bag in fully opened condition, ready for normal use; a portion of a wall of the bag has been cut away to illustrate the arrangement of the bottle-securing loops;

Fig. 4 is a vertical section taken on lines 4—4 of Fig. 3, except that the bag is shown in Fig. 4 in almost completely collapsed position;

Fig. 5 is a top plan section of the fully opened bag, taken at the location of the arrows 5—5 of Fig. 4, and showing the bottle straps as they would be when bottles are placed therein; and

Fig. 6 is a detail showing the corner construction of the bag and the method of affixing a bottle strap thereto.

Referring first to Fig. 3, a preferred embodiment of the bag 10 comprises rectangular end panels 11 and 12 and a preferably continuous elongate rectangular panel 14 which forms the side and bottom walls of the bag. As shown, compare Figures 3 and 2, the opened bag is substantially hexahedral, with a full-area mouth, but

may be collapsed into flat form. The material of the panels is preferably of waterproof plastic film, is of double thickness having a suitable filling therebetween, and is quilted to provide an attractive appearance and insulation qualities.

Tie strings 15 or equivalent which are threaded through grommets provided in the four sides of the bag afford means of gathering the top portion to a closed position while in use, and constitute a convenient handle for carrying.

Within the bag are disposed a pair of flat loops

16, 17 also desirably of quilted plastic material, which comprise bottle receiving receptacles. The said loops are secured, see Figs. 5 and 6, to the edges of the bag by a separate or integral strap 18, as desired, which forms a flexible hinge. The width of the bag is preferably such with relation to the width of the straps that the said straps do not overlap when the bag is folded flat, and the said straps are so positioned with respect to the depth of the bag that the latter, when flat, may be folded in half along a line represented by the top margin of the loops, further to reduce the area of the bag for storage in a bureau drawer or other relatively small space. Nevertheless the straps are of such width as to embrace a baby 15 bottle over a large central area thereof.

It will be noted from Fig. 5 that when the respective straps are opened to receive a bottle, each bottle held thereby is separated from its companion by a relatively wide space, making it impossible for the bottles to strike against each other while the bag is being carried. The quilted construction of the straps and of the bag material additionally protects the bottle against breakage and acts as a thermal insulation to minimize temperature change of the bottle contents.

Secured to the topmost edge of the bag at the side opposite the bottle straps is an open-topped envelope 20 which is preferably of transparent waterproof film. The width of this envelope is large in proportion to the width of the bag itself, and has a length at least equal to, and preferably slightly greater than, the length of the bag when the same is in collapsed or flattened position. As appears in Fig. 3, the envelope 20 is provided with spaced cutouts 21 so that the envelope will not interfere with the tie strings 15; the portions of the envelope material adjacent the cutouts are hinges permitting the envelope to be swung outwardly of the bag.

The envelope 20 is essentially for the storage of wet or soiled diapers, in order to prevent contamination of fresh diapers and other items which are contained within the bag. Importantly, however, the envelope 20 serves as a receptacle for the bag itself while the bag is in storage or is in shipment to the purchaser. Accordingly, see Fig. 2, the envelope 20 may be withdrawn from the bag and the bag itself folded thereinto. Then, the so-arranged structure may be retained in full size flat condition for demonstration purposes or folded on itself to provide the compact rectangular structure illustrated in Fig. 1. In any event, the transparent envelope 20 protects the delicate color of the bag against soilage or against shop-wear or damage during transit.

It is apparent, therefore, that I have provided a bag for infants' clothing and accessories which is of large volume when expanded, but nevertheless foldable into small size when used, and which has means optionally usable as a protective cover for the bag when not in use, or as a receptacle for soiled or wet garments.

5 Although the invention has been described by making a fully detailed reference to a certain presently preferred embodiment, such detail of description is to be understood in an instructive rather than a limiting sense, many changes being possible within the scope of the claims hereto appended.

I claim:

10 1. A bag for infants' garments and accessories, comprising a plurality of rectangular flexible panels united along their edges to provide a structure which may be collapsed into substantially flat form or opened into substantially hexahedron shape; bottle-receiving loops disposed at opposite edges of one of said panels, a single hinge-like strap for securing said loops to the said panel, said loops extending toward each other and of such size that when each receives a bottle, said bottles are secured in spaced relationship to each other; and a relatively large open-mouthed envelope of waterproof material disposed internally of said bag and secured therein only by engagement of an upper edge with an upper edge of one of said panels.

25 2. A bag for baby garments and accessories, comprising rectangular panels of waterproof, quilted, plastic film secured along their marginal edges to provide an open-topped hexahedral structure; tie cords threaded through the side walls of said structure at the top thereof to gather said side walls together for bag-closing purposes; a relatively deep loop of quilted material disposed internally of said bag and hingedly secured to a marginal edge thereof, said loop being adapted to embrace a bottle over a substantial length thereof; and an open-topped envelope of flexible waterproof material disposed internally of the bag and secured thereto only by securement of the upper edge of the outer wall of said 40 envelope with the upper edge of one wall of said bag, whereby said envelope may be brought to the exterior of said bag; said envelope having a mouth opening and a length and width sufficient to permit the bag itself to be disposed in the envelope in substantially flat form.
